HOLD-DOWN DOG

John L. Drake, Muskegon, Mich., assignor to
Ray W. Asbury, Grand Haven, Mich.

Application February 19, 1942, Serial No. 431,567

4 Claims. (Cl. 90—59)

The present invention relates to new and useful improvements in hold-down dogs for metal working machines, and has for one of its important objects to provide, in a manner as hereinafter set forth, a device of this character which may be expeditiously engaged with the work and which will firmly secure said work in any desired position.

Another very important object of the invention is to provide a hold-down dog of the aforementioned character which is adapted to be conveniently adjusted to meet various conditions.

Other objects of the invention are to provide a hold-down dog of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a hold-down dog constructed in accordance with the present invention, showing the device in use.

Figure 2 is a fragmentary view in top plan.

Figure 3 is a cross-sectional view, taken substantially on the line 3—3 of Figure 1.

Figure 4 is a vertical sectional view through one of the jaws, taken substantially on the line 4—4 of Figure 2.

Figure 5 is a vertical sectional view through one of the screw jacks or braces, taken substantially on the line 5—5 of Figure 2.

Figure 6 is a detail view in perspective of one of the posts.

Referring now to the drawings in detail, it will be seen that reference numeral 1 designates an elongated machine table. The table 1 has formed longitudinally in its upper surface a plurality of spaced, parallel, substantially T-shaped grooves 2. The upper surface of the table 1 is further provided with a plurality of sockets 3. The purpose of the grooves 2 and the sockets 3 will be presently set forth. A piece of work on the table 1 is indicated at 4.

Rising from the table 1 is a plurality of removable and slidably adjustable threaded posts 5. The posts 5 are provided with heads 6 on their lower ends which are operable in the substantially T-shaped grooves 2 in the table 1. Thus, the posts 5 are anchored to the table 1.

Mounted for sliding and rotary adjustment on the posts 5 are jaws 7 in the form of blocks of steel or other suitable metal. The fronts of the jaws 7 have formed therein dovetail channels 8 for the reception of correspondingly-shaped toothed faces 9. The faces 9 of the clamping jaws 7 are engageable with the work 4. Nuts 10 are threaded on the upper portions of the posts 5 for forcing the jaws 7 downwardly.

10 The jaws 7 further include protuberances 11 on their upper rear portions providing slightly inclined shoulders 12. Screw jacks 13 are engageable beneath the shoulders 12 for forcing the jaws 7 against the work. In the embodiment shown, the screw jacks 13 include male and female members 14 and 15, respectively, the former being threaded, as at 16, the latter including a smooth bore 17. The female member 15 further includes a substantially tapered lower end or base portion 18. A nut 19 is threaded on the portion 16 of the male member 14 and engaged with the upper end of the female member 15 for extending the jack.

20 Removable pins 20 are insertable selectively in 25 the sockets 3 in the machine table 1. Bearing against the pins 20 on the table 1 are bars 21. The lower end portions 18 of the jacks 13 are engageable with the bars 21, which bars prevent said jacks from slipping on the table 1.

30 It is thought that the manner of using the device will be readily apparent from a consideration of the foregoing. Briefly, the work 4 is placed at the desired location on the machine table 1 and the posts 5, with the jaws 7 thereon, are moved to a point adjacent thereto. The nuts 10 are then adjusted to the desired position on the posts 5 and the jacks 13 are engaged beneath the shoulders 12. Of course, the pins 20 are inserted in the proper sockets 3 in the table 1 and the bars 21 are placed thereagainst with the lower ends of the jacks engaged with said bars. The jacks 13 are then opened or extended for causing the jaws 7 to firmly clamp the work 4 therebetween, the toothed faces 9 biting into said work.

35 40 45 It is believed that the many advantages of a hold-down dog constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:
50 1. A hold-down dog of the character described

comprising a plurality of posts for the reception of a piece of work therebetween, jaws slidably mounted on said posts, adjustable stop nuts for the jaws threadedly mounted on said posts, and means for forcing the jaws against the work.

2. A hold-down dog of the character described comprising a plurality of posts for the reception of a piece of work therebetween, jaws slidably mounted on said posts, said jaws including toothed faces engageable with the work, adjustable stop nuts for the jaws threadedly mounted on the posts, said jaws further including protuberances providing shoulders, and screw jacks engageable with said shoulders for forcing the jaws against the work.

3. A hold-down dog of the character described comprising, in combination, a machine table having a plurality of spaced, parallel substantially T-shaped grooves therein and further having a plurality of sockets therein, a plurality of threaded posts removably and adjustably mounted on the table and adapted to receive a piece of work therebetween on said table, said posts including heads on their lower ends operable in the grooves in the table, pins engageable selectively in the sockets, bars adapted to be mounted on the table and engaged with said pins, jaws slidably mounted on the posts and including shoulders, adjustable stop nuts for the jaws threaded on the posts above said jaws, and means supported by said bars for forcing the jaws against the work.

5 sockets, bars adapted to be mounted on the table and engaged with said pins, jaws slidably mounted on the posts and including shoulders, adjustable stop nuts for the jaws threaded on the posts above said jaws, and screw jacks engageable at one end with the bars on the table and at their other ends with the shoulders for forcing the jaws against the work.

4. A hold-down dog of the character described 10 comprising, in combination, a machine table having a plurality of spaced parallel substantially T-shaped grooves therein and further having a plurality of sockets therein, a plurality of threaded posts removably and adjustably mounted on the 15 table and adapted to receive a piece of work therebetween on said table, said posts including heads on their lower ends operable in the grooves in the table, pins engageable selectively in the sockets, bars adapted to be mounted on the table and engaged with said pins, jaws slidably mounted on the posts and including shoulders, adjustable stop nuts for the jaws threaded on the posts above 20 said jaws, and means supported by said bars for forcing the jaws against the work.

JOHN L. DRAKE.
